UNITED STATES PATENT OFFICE

95,730

DESIGN FOR A REFRIGERATOR CABINET OR SIMILAR ARTICLE

John C. Buchanan, Detroit, Mich., assignor, by
mesne assignments, to Borg-Warner Corpora-
tion, a corporation of Illinois

Application August 19, 1933, Serial No. 49,068

Term of patent 14 years

To all whom it may concern:

Be it known that I, John C. Buchanan, a citizen
of the United States, and a resident of Detroit,
in the county of Wayne and State of Michigan,
have invented a new, original, and ornamental
Design for a Refrigerator Cabinet or Similar
Article, of which the following is a specification,
reference being had to the accompanying draw-
ing, constituting a part hereof.

Fig. 1 is a front perspective view of my new de-
sign of refrigerator cabinet; and

Figs. 2 and 3 are slightly enlarged partial sec-
tional views on the lines 2—2 and 3—3 of Fig. 1,
respectively, and illustrating the design of the
rounded edges of my refrigerator cabinet.

My new design for a cabinet is shown as em-

bodied in a refrigerator cabinet and is character-
ized by the widely rounded front side, top front
and top side edges, as clearly illustrated in Figs. 2
and 3, and by the rounded corners formed at the
junction of said edges.

The edges and corners are smoothly rounded
and are formed on a relatively large radius, so
that the absence of sharp corners and edges is
a dominant feature of the design.

I claim:

The ornamental design for a refrigerator cabi-
net or similar article, substantially as shown and
described.

In testimony whereof, I have hereunto sub-
scribed my name this 15th day of August, 1933.

JOHN C. BUCHANAN.
